STRETCHER

Hugh B. Johnson, Rochester, N. Y.

Application August 21, 1942, Serial No. 455,591

5 Claims. (Cl. 5—82)

(Granted under the act of March 3, 1883, as
amended April 30, 1928; 370 O. G. 757)

The invention described herein, if patented, may be manufactured and used by or for the Government for governmental purposes, without the payment to me of any royalty thereon.

The present invention relates to stretchers, and more specifically to a stretcher of an adjustable type, adapted to support a person in reclining position or in seated position.

It may be explained that when military forces are operating in mountainous regions, or over any rough, irregular, or treacherous terrain, considerable difficulty has been experienced in transporting injured persons from the area of military combat to hospitals or first aid stations where their injuries may be treated. Also, under such conditions, some difficulty may be encountered in transporting a stretcher over hazardous terrain to reach the location of an injured person.

It is, therefore, the principal object of the present invention to provide a novel and improved stretcher including primary and secondary frame members arranged to be shiftably associated with each other, so that an injured person may be comfortably carried in prone or seated position.

Further, it is an object of the invention to provide such stretchers wherein the adjustment of the stretcher to either position may be made easily and quickly.

A further object of the invention resides in the provision of a stretcher designed so that it may be readily folded into a collapsed position, to form a compact bundle or pack that may be easily carried by one soldier.

A further object of the invention resides in the provision of a collapsible stretcher of light weight, rugged construction, and well adapted to economical methods of mass production.

It is also an aim of the present invention to provide a novel stretcher device of such mechanical design and construction that it may be constructed almost entirely of wood, or other non-critical material, in order that scarce materials may be released for use in other military equipment.

Other objects will appear hereinafter.

Referring now to the single sheet of drawings attached to and forming a part of the present specification,

Fig. 1 is a perspective view of a stretcher constructed in accordance with the teachings of this disclosure, the stretcher being positioned to support a person in sitting posture.

Fig. 2 is a longitudinal sectional view of the stretcher illustrated in Fig. 1, the several parts

being shown in position to support a person in reclining position.

Fig. 3 is a longitudinal sectional view of the stretcher, the several parts being shown in collapsed or folded position.

Fig. 4 is a detail perspective view of the central hinge on one of the stretcher's side rails.

The stretcher comprises, in general, a primary frame consisting of a pair of joined side rails spaced apart by suitable cross members and including carrying handles at each end of each rail, together with a shiftable secondary frame in pivoted relationship with the primary frame and so constructed and arranged as to support a fabric stretcher surface in either of two positions; in one of which the stretcher is adapted to support a person in reclining or prone position, and in the other of which the stretcher is adapted to support a person in seated position.

20 In the drawing, the fabric stretcher surface has been omitted, or indicated by dotted lines, in order to more clearly illustrate the frame structure, wherein the novel features of the present invention reside.

25 Each of the side rails of the main or primary stretcher frame includes a front rail 11 and a rear rail 12 hinged together by a central hinge 13 and provided with front and rear handle portions 14 and 15, respectively. The hinge 13 includes an offset pivot pin 16, so that the rails 11 and 12 may be hinged to lie flat against each other, for reasons that will be apparent from the following description. The hinge is also preferably provided with registering openings 17 and 18, so that a locking pin 19 may be inserted through the hinge to maintain the sections 11 and 12 of each side rail in rigid end-to-end relationship.

30 The two opposite side rails of the primary frame of the stretcher are spaced apart by rigid cross braces 21 and 22 adjacent the front and rear ends of the frame, respectively, and, if desired, transverse webbing straps 23 and 24 may be stretched between the side rails to facilitate carrying the stretcher.

35 The secondary frame of the stretcher includes, in general, a back rest and a seat portion. These are pivotally mounted with respect to the primary frame and pivoted to each other so that the secondary frame may be shifted into either of the two carrying positions.

40 The back rest of the stretcher consists of a pair of side members 25, each pivoted on one of the rails 12 of the primary frame by means of a fixed rivet 26. The upper ends of the side mem-

bers (as seen in Fig. 1) are joined by a cross brace 27 and the lower end of each of the side members includes a spacer structure 28 having two relatively flat supporting surfaces 29 and 30. It will be noted from a comparison of Figs. 1 and 2 that the weight of the stretcher when positioned to support a person in sitting position may be rested on a surface 29, while when the stretcher is in position to support reclining person it may be rested on the surface 30.

The seat portion of the stretcher comprises two side rails 32, each pivoted to the lower end of one of the side members 25 by a rivet 33. The side rails 32 are connected with one of the side rails 11 of the primary frame by a pin and slot connection including a rivet 34 adapted to pass through and slide in the slot 35. A transverse knee support 36 extends between the ends of the side rails 32 at the forward end of the seat portion. Spacing blocks 37 are provided so that the side rails 32 will be properly aligned with the inner surface of the side members 25 of the seat back.

The stretcher fabric, indicated in dotted lines at 38, is secured to the cross brace 21 at the forward end of the stretcher, and extends across the knee support 36 and thence to the cross brace 21 so as to provide a full supporting surface for the entire length of the body of the patient, whether the stretcher is used in sitting position, such as illustrated in Fig. 1, or when the parts are shifted to accommodate the patient in reclining position, as illustrated in Fig. 2.

The main frames 12 and the side members 25 are provided with drilled openings 41 and 42, respectively, so that the secondary frame may be positively locked in the position shown in Fig. 2 by bringing these openings into registry and inserting a locking pin, similar to the locking pin 19 illustrated in Fig. 4. Similar openings 43 are provided in the seat slides 32 and the side rails 11, so that the stretcher assembly may be locked in the position illustrated in Fig. 1 by use of locking pins 44 inserted through these openings.

It has been heretofore pointed out that one of the objects of the present invention was a provision of a stretcher so arranged and constructed that it could be quickly and easily converted in order to carry a person either in reclining position or in seated position; the latter possessing obvious advantages under certain conditions, as for example, in cases in which it becomes necessary to manually carry the stretcher down steep inclines, such as abrupt mountain slopes, or when it becomes necessary to lower the entire stretcher by means of ropes or cables.

It has also been pointed out that one of the aims of the present invention was a provision of a collapsible stretcher frame so arranged that it could be conveniently folded into a pack sufficiently small so that it could be carried over difficult terrain by one man. The present structure meets this requirement admirably, since the entire stretcher may be easily folded into the position illustrated in Fig. 3, so that it may be easily carried, even in mountainous country where transportation of conventional types of stretchers by one man is a practical impossibility. In this connection it will be noted that rivet 33 on each of the side members 25 is located a distance from the rivet 26 equal to the spacing between the rivet 26 and the hinge pin

16. Thus, when it is necessary to fold the stretcher into a collapsed position, the rivets 33 may be moved into co-active position with respect to the king pin 16, and the entire stretcher, including the primary frame and secondary frame, may be folded simultaneously. When in this position, the two frames are quite compactly nested together and form a comparatively small pack that may be carried by one man.

10 It may be noted, in passing, that the present device has been specifically designed to meet present military requirements and that the exact structure illustrated in the drawings is believed to be most satisfactory for the purpose. Nevertheless, the principles of the invention are believed to extend to civilian uses as well as military, and the structure of the device is subjected to some modification without departing from the teachings of the present disclosure. It 15 is accordingly requested that the scope of the invention be regarded as limited only by the terms of the appended claims.

Having thus described my invention, what I claim as new and desire to secure by Letters 20 Patent is:

1. In a stretcher construction having a main frame including a pair of side rails maintained in spaced relationship, each side rail comprising a pair of hingedly connected sections, a body supporting frame comprising a seat member and a back rest member, means pivotally connecting the back rest member to the side rails of the main frame intermediate the ends of one pair of said sections, means pivotally connecting the seat 25 member to the side rails of the main frame intermediate the ends of the other pair of said sections, means pivotally connecting the back rest member and the seat member, one of said pivotally connecting means being of the lost motion type whereby said seat member and said back rest member may be moved into angular relationship with respect to each other and to said main frame or into substantially parallel relation to the side rails of the main frame, the 30 distance between the pivotal connection of the back rest member to each of the side rails and the pivotal connection of the back rest member to the seat member being substantially equal to the distance between the hinge connecting 35 the sections of each of the side rails and the pivotal connection of the back rest member to each of the side rails comprising the main frame whereby the main frame and the body supporting frame may be folded to permit easy transportation.

2. In a stretcher construction having a main frame including a pair of side rails maintained in spaced relationship, a body supporting frame comprising a seat member and a back rest member pivotally attached to each other, means pivotally connecting the back rest member to the side rails of the main frame, lost motion pivot means connecting the seat member and the side rails of the main frame, whereby said seat member and said back rest member may be moved into angular relationship with respect to each other and to said main frame or into parallel relationship to the side rails of the main frame, locking means to lock said back rest member and seat member to the side rails when the said members are in said angular relationship, and additional locking means to lock said back rest member and seat member to the side rails when said members are in parallel relation to said side rails.

3. In a stretcher construction having a main frame including a pair of side rails maintained in spaced relationship each side rail comprising a pair of hingedly connected sections, a body supporting frame comprising a seat member and a back rest member, the back rest member having a pair of spaced side rails, means pivotally connecting said back rest side rails to the side rails of the main frame intermediate the ends of one pair of said sections, the seat member having a pair of spaced side rails, means pivotally connecting the seat member to the side rails of the main frame intermediate the ends of the other pair of said sections, means pivotally connecting the side rails of the back rest member and the side rails of the seat member, one of said pivotally connecting means being of the lost motion type whereby said seat member and said back rest member may be moved into angular relationship with respect to each other and to said main frame or into substantially parallel relation to the side rails of the main frame, the distance between the pivotal connection of the back rest side rails to the side rails of the main frame and the pivotal connection of the back rest side rails to the side rails of the seat member being substantially equal to the distance between the hinge connecting the sections of each of the side rails and the pivotal connection of the back rest side rails to each of the side rails comprising the main frame whereby the main frame and the body supporting frame may be folded to permit easy transportation.

4. In a stretcher construction having a main frame including a pair of side rails maintained in spaced relationship, each side rail comprising a pair of hingedly connected sections, a body supporting frame comprising a seat member and a back rest member, the back rest member having a pair of spaced side rails, means pivotally connecting said back rest side rails to the side rails of the main frame intermediate the ends of one pair of said sections, the seat member having a pair of spaced side rails, means pivotally connecting said seat member side rails to the side rails of the main frame intermediate the ends of the other pair of said sections, means pivotally connecting the back rest member and the rails of the seat member, one of said pivotally connecting means being of the lost motion type whereby said seat member and said back rest member may be moved into angular relationship with respect to each other and to said

main frame or into substantially parallel relation to the side rails of the main frame, the distance between the pivotal connection of the back rest side rails to the side rails of the main frame and the pivotal connection of the back rest side rails to the side rails of the seat member being substantially equal to the distance between the hinge connecting the sections of each of the side rails and the pivotal connection of the back rest side rails to each of the side rails comprising the main frame whereby the main frame and the body supporting frame may be folded to permit easy transportation.

5. In a stretcher construction having a main frame including a pair of side rails maintained in spaced relationship, each side rail comprising a pair of hingedly connected sections, a body supporting frame comprising a seat member and a back rest member, means pivotally connecting the back rest member to the side rails of the main frame intermediate the ends of one pair of said sections, means pivotally connecting the back rest member and the seat member, means pivotally connecting the seat member and the side rails of the main frame, intermediate the ends of the other pair of said sections, one of said pivotal connections being of the lost motion type whereby said seat member and said back rest member may be moved into angular relationship with respect to each other and to said main frame or into substantially parallel relation to the side rails of the main frame, the distance between the pivotal connection of the back rest member to each of the side rails of the main frame and the pivotal connection of the back rest member to the seat member being substantially equal to the distance between the hinge connecting the sections of each of the side rails and the pivotal connection of the back rest member to each of the side rails comprising the main frame whereby the main frame and the body supporting frame may be folded to permit easy transportation, locking means to lock said back rest member and seat member to the side rails of the main frame when said members are in said angular relationship, and additional locking means to lock said back rest member and seat member to the side rails of the main frame when said members are in substantially parallel relationship to said main frame side rails.

HUGH B. JOHNSON.
